EDWARD F. KUHNS, OF TREVORTON, PENNSYLVANIA.

SNAP-HOOK.

1,250,596.

Specification of Letters Patent. Patented Dec. 18, 1917.

Application filed July 30, 1917. Serial No. 183,580.

To all whom it may concern:

Be it known that I, EDWARD F. KUHNS, a citizen of the United States, residing at Trevorton, in the county of Northumberland and State of Pennsylvania, have invented certain new and useful Improvements in Snap-Hooks, of which the following is a specification.

This invention relates to snap-hooks and more particularly to an improved construction for the same whereby the different parts may be easily assembled and placed in operative position and which will eliminate the possibility of injured parts making the snap-hook permanently defective.

One of the objects of the invention is to provide a snap-hook of this character having the body portion adapted to receive the sliding bolt in the usual manner, the improved construction being in the particular manner by which the bolt is placed into operative position; the manner in which the bolt is resiliently held within its position; and the simplicity of the construction for permitting repairing of the parts should they become defective.

A further object of this invention is the provision of a snap-hook which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a perspective view of the device constructed in accordance with my invention.

Fig. 2 is a side elevation, partly in section disclosing the interior construction of the device.

Referring to the drawing, wherein is illustrated the preferred form of my invention, and in which like numerals of reference indicate corresponding parts throughout the several views, the body 1 of the snap hook is designed generally after the shape of the ordinary snap-hooks of this character and includes the barrel 2 and the retaining hook 3. The barrel 2, as shown, particularly in Fig. 2 of the drawing, has an interior cylindrical bore 4 extending the full length

and open at both ends of the barrel. The terminal 5 of the hook 3 is in longitudinal alignment with the center of the bore 4. The end of the barrel, nearest to the terminal 5 of the hook is sufficiently spaced from the latter to provide a relatively wide gap 6. The opposite end of the barrel is integrally connected with a loop 7 which, of course, would be fastened in any desired manner to the strap or article with which the snap-hook is to be used. The loop 7, however, is offset laterally to the end of the barrel that it is positioned to one side of the longitudinal center line of the barrel as shown to advantage in Fig. 2.

A sliding bolt 8 is constructed to fit slidably within the bore 4 of the barrel and the position of the loop 7 as above stated, permits the bolt to be slid into the bore from the end of the barrel nearest the loop 7. A longitudinal slot 9 is formed in the barrel and extends from a point near the inner end thereof through its outer end. This slot receives and guides the shank 10 of a T-shaped finger or thumb knob 11 through the medium of which the bolt may be reciprocated. The sliding bolt is constructed to extend beyond the inner end of the barrel and contacts with the terminal 5 of the hook 3 to close the gap 6.

The open end 4' of the bore 4 is closed by a closure plate 12 which is of circular formation so that it fits snugly over the end of the barrel to effectively close the bore. This plate is integrally connected to a filler arm 13 which projects into the slot 9 to close the greater portion thereof after the bolt 8 has been placed in position within the bore, said slot being open to permit the insertion of the bolt carried finger. A coil spring 14 is first inserted in the bore so that when the plate 12 is mounted in position the ends of the spring will bear against the plate and the end of the bolt and operate to normally project the bolt. The filler arm 13 has a lug 15 through which a pin or rivet 16 is extended and the ends of this rivet are received in apertured lugs 17 disposed at opposite sides of the slot near the end thereof. This rivet is thereby made to hold the filler arm 13 removably in position in the slot. Sufficient space is left between the end of the filler arm and the neck 10 to permit the latter to be moved for opening the gap 6 when the bolt is moved to open position. It will be noted that this rearward move-

ment of the bolt causes the spring to compress and the same bears against the plate 12, but no pivotal action of the filler arm can occur since the end of the same is slightly 5 extended over the proximate end of the bolt 8 as shown to advantage in Fig. 2, the length of the bolt being greater than the distance between the bill of the hook and the inner end of arm 13.

10 This simple and durable construction provides an efficient snap-hook and it is to be noted that by simply removing the pin 16, all of the working parts may be quickly dismantled. This is especially advantageous 15 where heavy snap-hooks are used for heavy work such as drawing heavy loads where the parts often buckle and bend and become quickly defective. In this event any one of the simple parts may be quickly replaced 20 by simply removing the pin 16 and replacing the injured part after which the pin may be replaced and the hook will be as strong as ever.

From the foregoing it will be observed 25 that a very simple and durable snap-hook has been provided, the details of which embody the preferred form. I desire it to be understood, however, that slight changes in the minor details of construction may be 30 made without departing from the spirit of the invention or the scope of the claims hereunto appended.

Claims:

35 1. In a snap hook, the combination of a barrel having a hook formed at one end and a loop formed at its other end, said barrel having a longitudinal bore opening through the ends thereof, a bolt mounted

to slide within the barrel and to engage the bill of the hook for closing the hook, a closure plate mounted over the rear end of the barrel for closing the bore thereof, a coiled spring mounted in said bore between said bolt and plate for projecting the bolt, and means for removably securing said closure plate in operative position. 40 45

2. In a snap hook, the combination of a barrel having a hook formed at one end, the bore of the barrel opening through both ends, said barrel having a longitudinal slot opening through its rear end, a sliding bolt mounted in said barrel, means carried by the bolt and projecting through the slot for permitting reciprocation of the bolt from outside the barrel, a closure plate mounted over the rear end of said barrel and closing said end, a coiled spring interposed between the plate and the end of said bolt for holding the bolt normally in projected position to engage the bill of said hook, a filler arm carried by said plate and arranged within said slot, and a removable pin extending transversely through said arm and barrel to removably secure the closure and arm, the length of the bolt being greater than the distance between the bill of the hook and the inner end of said filler arm to provide for the supporting of the latter by the former to prevent pivoting of said arm. 50 55 60 65

In testimony whereof I affix my signature 70 in presence of two witnesses.

EDWARD F. KUHNS.
